OTHER PUBLICATIONS

Design U.S. Appl. No. 29/439,272, filed Dec. 9, 2012, Eldad Eilam, Graphical User Interface Icon.

(Continued)

Primary Examiner — Kevin Rudzinski(74) *Attorney, Agent, or Firm* — Lewis Roca Rothgerber LLP(57) **CLAIM**

The ornamental design for a display screen with graphical user interface icon, as shown and described.

DESCRIPTION

The FIGURE is a front view of the display screen with graphical user interface icon.

Any portion of the FIGURE illustrated in hashed lines pertains to the display screen and thereby constitutes non-claimed subject matter. Those portions of the FIGURE (if any) do not constitute a part of the claim and are presented solely for context.

1 Claim, 1 Drawing Sheet(56)
